UNITED STATES PATENT OFFICE.

ADONIRAM J. COLLAR, OF YREKA, CALIFORNIA.

WATER-GATE.

No. 823,991.

Specification of Letters Patent.

Patented June 19, 1906.

Application filed August 24, 1905. Serial No. 275,602.

To all whom it may concern:

Be it known that I, ADONIRAM J. COLLAR, a citizen of the United States, residing at Yreka, in the county of Siskiyou and State of California, have invented new and useful Improvements in Water-Gates, of which the following is a specification.

My invention relates to improvements in water-gates for ditches, canals, restraining dams, reservoirs, and the like.

Great difficulty is often experienced in opening and closing ordinary water-gates of large size owing to the amount of power required. Furthermore, where a very considerable head of water is to be controlled, as in canals and other places, it is necessary to use a number of ordinary gates, each gate with its separate passage-way and complement of wood, iron, or masonry-work. This is very expensive, besides being objectionable in flood time by reason of the obstructions thereby offered across the stream to logs, brush, weeds, and other floating debris which have a tendency to clog the gates and possibly result in most serious damage, as by overflow.

It is the object of my invention to provide a gate capable of controlling a far greater flow of water than any other single gate of which I have knowledge, which requires little or no manual exertion to open or close, which offers no obstruction to the passing flood, and which is simple in construction, durable, and practical.

It consists of the parts and the construction and combination of parts, as hereinafter more fully described and claimed, having reference to the accompanying drawings, in which—

Figure 1 is a longitudinal vertical section of my apparatus. Fig. 2 is a plan view of same. Fig. 3 is a front side view of the gate and wells, omitting certain parts of the apparatus. Fig. 4 is a view similar to Fig. 3 of a modification of the invention.

45 A represents a ditch, canal, head of a reservoir, or any water-container through or from which a certain and determinate supply is adapted or desired to be passed either continually or periodically.

50 2 is a gate, shown as a flat plate seating on the slightly-inclined seats 3. The latter may be of wood, stone, or metal, or built into the concrete foundations or formed in the sides and bottom of the canal or ditch. When the 55 gate is closed, it is supported on its seat on the

sides and bottom, and, if desired, a suitable rubber or like gasket may be carried by one or the other of the contiguous parts to insure a tight joint. The gate may be of wood or metal and of any desired size, and it may be 60 rectangular, as here shown, or any other suitable shape.

Arranged at a suitable distance behind the gate and somewhat above the center of the gate, and preferably out of all interference 65 with the passing flood beneath, are the cross-beams 4. These beams are suitably anchored and braced or trussed and may be of wood or metal and of such construction, like the gate, commensurate with the strain to be 70 put upon them.

Pivoted to the beams 4 or to any other suitable support are the radius rods or beams or frames 5, their size and character depending on their specific construction and the latter depending on the size of the gate. I shall term them "rods" in this specification, and that is understood to cover all sizes and forms of construction. These radius-rods are preferably arranged in series, with two or more 80 disposed in the same vertical plane in each series. The rear ends of the rods 5 are pivotally connected to the cross-beams 4, as at 6, and the forward ends of the rods are pivotally connected to the gate, the upper rods of 85 the several series near the top of the gate and the lower rods of the series near the bottom of the gate. The disposition of the pivots 6 of the rods relative to the gate and to the inclination of the latter when closed is such 90 that with the gate closed the rods will tilt downward from pivots 6 and include acute angles between their upper edges and the portion of the gate above the rods. In other words, the gate passes over center in seating, 95 and on the lifting of the rods to turn them on their pivots 6 the gate is made to swing out from its seat in an arc described from pivots 6. This is for the purpose of starting the gate from its seat before attempting to open 100 it, since otherwise in a big gate ten or twenty feet, more or less, in length and five or more feet in depth it would be almost impossible to slide a gate upward on its seat, owing to the tremendous thrust exerted by the body of 105 water.

The manner of attaching the rods to the gate and their mode of operation are as follows: The front end of each rod instead of being perfectly square is slightly inclined, so 110

that the lower edge of a rod is a trifle longer than the upper edge. A stirrup 7 is secured to and projects beyond the forward end of each rod and incloses and houses an end of a 5 long roller 8. There are two or more of these rollers, depending on the number of rods in a series, and extending parallel and across the 10 back of the gate. These rollers are supported thereon to have a limited up-and-down movement transverse to their length in the 15 guides or stops 9.

I have here shown for simplicity of operation but two rollers and but two series of radius-rods and but two rods in each series. 15 Obviously I may multiply these parts as the exigencies of any particular case may require. The rollers are supported between the ends of the rods and the gate by the stirrups 7 and bear on metal plates 10 on the 20 gate. The function of the rollers is that of antifrictional bearings. The stirrups 7 are of such form and size as to permit a limited movement of the forward ends of the rods independent of the rollers. When the gate is 25 closed, the rollers rest on the bottom of the guides 9 on the gate, and the front ends of the rods are supported on the rollers at the top of the stirrups or housings 7, the rollers being pressed against the ends of the rods by the 30 thrust of the water on the gate. Lifting the rods causes the rollers to roll up on the plates to the top of the guides 9 and down on the ends of the rods to the bottom of the stirrups 7, the rods thus having an oscillatory movement 35 independent of the gate and equal to the travel of the rollers in the guides 9 plus the travel of the rollers in the stirrups 7. This independent oscillatory movement of the rods results in a forward or horizontal 40 non-oscillatory movement of the gate away from its seat and against the body of restrained water. This preliminary forward movement of the gate to free it from its seat, and thereby make it easier to open, results, 45 as before indicated, from the elevated position of the rear pivots 6 of the rods and the general arrangement of the parts which permits the gate to stand below its center of oscillation when closed. Naturally when the 50 rods are lifted their forward ends describe an arc upward and toward the body of restrained water, and the loose pivoting of the rollers in the stirrups 7 and guides 9 permits a movement of the gate substantially at right angles to its seat prior to its being lifted. The 55 gate is preferably arranged with its top slightly backwardly inclined from the perpendicular when closed, so that as the gate is lifted the water escaping beneath the gate 60 will assist in its further opening. The amount of incline of course that is given to the gate and its seats is proportionate with the pressure, the means to close the gate, and the various other agencies and instrumentalities 65 needing consideration. Any appropriate

means whatever may be employed to turn the radius-rods on their pivots 6 to cause the gate to open and close. I prefer to have the means for operating the gate work automatically as far as possible and to that end have 70 here shown certain hydraulic appliances for that purpose.

11 represents two receptacles or wells disposed one on each side of and a little behind the gate, with a float 12 operating in each. 75 Each float is provided with an upright stem 13, suitably perforated, as shown at 14. The radius-rods are pivotally connected to vertical standards 15, which support a cross-head 16, having arms extending out to either side 80 and over a respective well 11 and along the side of a float-stem 13.

The ends of the cross-head 16 have each a suitable means, as shown at 17, to engage a perforation in the stem 13. The points of connection of the stem to the cross-head determines the amount the gate is to be opened, since it is designed that if the float is disconnected near to the cross-head it will open the gate a less distance than if a longer amount 90 of stem intervenes between a float and the cross-head. Water is let into the wells to raise the floats simultaneously, and it is discharged therefrom to allow the floats to fall and close the gate by the following means: 95 At a suitable point I have shown a tank 18, connected with the body of restrained water through a conduit or pipe 19, having a discharge downward into the tank. The latter has an outlet 20 in its bottom, and I have 100 shown a valve 21, which is adapted alternately to open or close the inlet 19 and correspondingly close or open the discharge 20. The inlet 19 and the discharge 20 are disposed in vertical line, and the valve 21 is 105 made with a double seating portion and is supported to reciprocate between the inlet 19 and the discharge 20, being connected to a stem 22, sliding in suitable guides 23. Any suitable means may be employed to reciprocate the stem and valve. 110

The two wells 11 are connected near their bottom, as shown at 24, and the tank 18 is connected with the wells, as at 25, at some suitable point below the inlet 19. When 115 valve 21 is seated over the outlet 20, water under control in the canal or reservoir may flow into tank 18 and thence into wells 11 to raise the floats. If the floats are connected with the cross-head 16, the radius-rods will 120 be lifted and the gates opened. The amount that the gates shall open may be determined, as before indicated, by attaching the stems 13 at the proper point to the cross-head, since the floats will always rise to the level of the 125 restrained body of water. When it is desired to close the gate, the valve is moved to close the inlet 19 and open the discharge 20, whereupon the wells 11 are gradually drained, and the gate is closed by the weight of the falling 130

floats suspended on the cross-head. The weight of these floats is sufficient always to close the gate irrespective of the volume of water confined.

5 In order to adjust the float relative to the cross-head, and so vary the opening of the gate, a sufficient body of water is let into the wells just to buoy up the floats and not press up on the cross-head, so that the stems can be 10 easily disengaged from their attachments 17. Then by letting in more water or discharging some the floats may be raised or lowered and again connected to the cross-head. In order that this gate may operate automatically in 15 the event of flood, or if for any other reason it is desired to open the gate whenever the water approaches the top of the gate, I provide an overflow connection 26, discharging into the tank 18. If the amount of this 20 overflow is in excess of the discharge through 20, this excess will pass into the wells 11 and evenly lift the floats and correspondingly open the gate. As the level of the restrained water falls below the overflow 26 the wells 25 will drain themselves and the gate will evenly close.

It is the design of my invention that whenever the gate is in its normal position the wells should be emptied. Thus if the closed position is said to be the normal position of the gate then the wells will be emptied, as I have just described. If the normal position of the gate is its open position, as might be under some circumstances, it is desirable then also 35 that the wells should be emptied and that the closing of the gate should be effected by a flooding of the wells, which is just the reverse of the previously-described operation.

In Fig. 4 I have indicated a construction 40 which adapts the gate to operate to close when the floats rise. The only change here necessary is the interposition of some means, as the levers 16^a, between the ends of the cross-heads 16' and the float-stems 13'. Inasmuch as the same construction of radius-rods 45 for supporting and lifting the gates and the same valve means for flooding the wells are employed in this case as is shown in Figs.—, I do not deem it necessary here to redescribe 50 nor show them. It will be understood, however, that when the inlet 19 is open and the outlet 20 closed the water will flow into the cylinders 11^a to raise the floats and close the gate.

55 It is possible that various modifications in my invention may be made without departing from the principle thereof, and I do not wish to be understood as limiting myself to the specific construction as herein shown and 60 described.

Having thus described my invention, what I claim, and desire to secure by Letters Patent, is—

65 1. A gate provided with suitable seats, means for moving said gate horizontally to

free it from its seats and then vertically to open the gate, said means including radius-rods pivotally connected to the gate and fulcrumed at one side of the latter.

2. The combination with a conduit of a 70 gate seating therein, said gate slightly inclined downward in the direction of current-flow, and means for giving said gate first a limited horizontal movement in the direction of waterthrust and then a transverse movement to open the gate, said means including radius-rods pivotally connected with the gate and having their fulcra at one side of and above the center of the gate. 75

3. The combination with a conduit of a 80 gate seating therein, radial members pivotally connected with the gate and fulcrumed at one side thereof, and means for operating said members to open the gate.

4. The combination with a conduit of a 85 gate seating therein, radial members pivotally connected with the gate and fulcrumed at one side thereof, and hydraulic means connected with a conduit to operate said members to open the gate. 90

5. The combination with a conduit of a 95 gate seating therein, radial members pivotally connected with the gate and fulcrumed at one side thereof, said pivotal connections between said members and the gate permitting of a limited oscillatory movement of the members and a corresponding but non-oscillatory movement of the gate. 95

6. The combination in a conduit of a gate seating therein, radial members fulcrumed at 100 one side of the gate and roller-bearing, and pivotal connections between said members and the gate.

7. The combination with a conduit of a 105 gate seating therein, radial members fulcrumed at one side of the gate, and rollers interposed between the ends of said members and the gate, and means on the gate and members to support said rollers.

8. The combination with a conduit of a 110 gate seating therein, radial members fulcrumed at one side of the gate and pivotally connected with the latter, said pivotal connections including rollers interposed between the ends of said members and the gate and 115 having a limited movement independent of said members.

9. The combination with a conduit of a 120 gate seating therein, radial members fulcrumed at one side of the gate and pivotally connected with the latter, said pivotal connections including rollers interposed between the ends of said members and the gate and having a limited movement independent of said gate. 125

10. The combination with a conduit, of a gate seating therein, and means to open said gate, said means including a radius member fulcrumed at one side of the gate and having a beveled end proximate to the gate, and 130

means for supporting said roller on the gate and on said beveled end to permit movement of the roller across said beveled end.

11. The combination with a conduit of a gate seating therein, and means for operating said gate, said means including upper and lower radial members fulcrumed at one side of the gate and above the horizontal center thereof, and having pivotal connections respectively near the top and bottom of the gate.

12. The combination with a conduit of a gate seating therein, and means for operating said gate, said means including upper and lower radial members fulcrumed at one side of the gate and above the horizontal center thereof, said members having pivotal connections with the gate respectively near the top and bottom of the gate, and means for turning said members on their fulcra.

13. The combination with a conduit of a gate seating therein, and means for operating said gate, said means including upper and lower radial members pivoted at one side of the gate and above the horizontal center thereof, and pivoted to the gate respectively near the top and bottom of the gate, and hydraulically-operated connections with the restrained fluid in the conduit for operating said members.

14. The combination with a conduit of a gate seating therein, and means to operate said gate, said means including radial members pivotally connected with the gate, a receptacle, a float in said receptacle, connections between the float and said radial members, and means for charging and discharging said receptacle to reciprocate the float.

15. The combination with a conduit of a gate seating therein, radial members connected with the gate, receptacles on opposite sides of the gate, floats in said receptacles, connections between the floats and the radial members, and means for charging and discharging said receptacles to reciprocate the floats and open or close the gate.

16. The combination with a conduit of a gate seating therein, radial members pivotally

connected with the gate, receptacles on either side of the gate, floats in the receptacle, 50 adjustable connections between the floats and the members, and valve-controlled connections between the conduit and the receptacles to charge and to discharge the latter.

17. The combination with a conduit of a 55 gate seating therein, radial members connecting with the gate, receptacles on either side of the gate, floats in said receptacles, stems on said floats, adjustable connections between said stems and the radial members, and connections between the conduit and the receptacles to operate the gate automatically.

18. The combination with a conduit of a 60 gate seating therein, radial members pivotally connected with the gate, receptacles on 65 either side of the gate, floats in said receptacles, a tank connected with the receptacles and with the conduit, said tank having an outlet and a valve operating to control both the inlet and outlet of said tank.

19. The combination of a gate having inclined seats, radial members fulcrumed at one side of the gate and above the horizontal center thereof, and hydraulically-operated means for oscillating said members to open and 75 close the gate.

20. The combination with a conduit, of a 80 gate seating therein, and means to open said gate, said means including a radius member fulcrumed to one side of the gate and having 85 a beveled end proximate to the gate, a roller interposed between said beveled end and the gate, means for supporting said roller on the gate and on said beveled end to permit movement of the roller across said beveled end, 85 and hydraulically-operated connections between said member and the restrained fluid in the conduit.

In testimony whereof I have hereunto set my hand in presence of two subscribing witnesses.
